UNITED STATES PATENT OFFICE.

JOHN F. DE HAVEN, OF EAST LIVERPOOL, OHIO.

CURTAIN-BRACKET.

1,192,281.

Specification of Letters Patent. Patented July 25, 1916.

Application filed February 29, 1916. Serial No. 81,199.

To all whom it may concern:

Be it known that I, JOHN F. DE HAVEN, a citizen of the United States, residing at East Liverpool, in the county of Columbian and State of Ohio, have invented new and useful Improvements in Curtain-Brackets, of which the following is a specification.

The present invention relates to improvements in the construction of curtain brackets, and the primary object of the invention is to construct a bracket of this character which can be attached to the window casing without marring or defacing the same and which is subject to adjustment approximately equaling the width of the vertical members of the window casing whereby the same may accommodate various lengths of shade rollers or curtain poles.

A further object of the invention is to produce a device of this character which shall embody the desirable features of simplicity in construction, cheapness in manufacture, ease of application and thorough efficiency in application.

A still further object of the invention is to produce a window bracket of this character which can be readily attached without the employment of screws, nails or analogous securing devices.

With the above and other objects in view, the improvement resides in the construction, combination and arrangement of parts set forth in the following specification and falling within the scope of the appended claims.

In the drawing: Figure 1 is a perspective view illustrating the application of the improvement, Fig. 2 is a vertical sectional view through the casing and in a line with the hanger member of the bracket, Fig. 3 is an enlarged sectional view approximately on the line 3-3 of Fig. 2, and Fig. 4 is a detail sectional view approximately on the line 4-4 of Fig. 3.

Referring now to the drawing in detail the numeral 1 designates an ordinary window casing which has at its opposite ends a combined shade roller and window curtain support or bracket constructed in accordance with the present invention.

The brackets each include a hanger formed from a flat plate comprising an outer or vertical member 1 which has an inwardly extending top or flange 2 provided with a downturned lip 3 that is adapted to be received between the inner face of the top

member of a window casing and the surface against which the casing is secured, while the plate 1 rests against the outer surface of the casing. The plate 1 at its lower end is formed with outwardly extending angularly disposed spaced spring fingers 4 and 5 respectively, the purpose of which will presently be described. Formed upon the plate 1 and extending outwardly therefrom is a curtain pole supporting member 6 and a shade roller supporting member 7.

The lower or guide brace members for the bracket are designated by the numerals 8 and 9 respectively. Each of these members is formed from a flat strip of suitable material, metal preferred, and has its edges extended angularly toward each other, as indicated by the numerals 10 and 11 respectively. These bent edges provide guide flanges and the flanges 10 of the member 8 are engaged by the spaced pairs of spring fingers 4 and 5 of the hanger member and the said flanges of the member 8 also serve to receive the flanges 11 of the member 9. The flanges 10 of the member 8 are adapted to exert an inward pressure or tension and the flanges 11 of the member 9 are adapted to exert an outward tension so that it will be noted that the flanges of the respective members exert a tension one against the other and thus provide a frictional engagement between the members 8 and 9.

The numeral 12 designates a locking element which is in the nature of a screw and which engages with a thread in an opening in the member 9 and is adapted to have its end contact with the outer face of the member 8 to move the said plate 9 to bring its edges or flanges into frictional engagement with the flanges 11 of the member 8.

Each of the members 8 and 9 have their outer ends flanged, as indicated by the numerals 13 and 14 respectively, and these flanges are formed with inturned teeth 15 and 16 respectively, the said teeth being disposed to engage between the inner edges of the vertical members of the casing and the surface to which the casing is secured.

By reference to the drawings it will be noted that the spring fingers 4 and 5 of the hanger member are arranged in pairs, one pair being disposed adjacent each of the longitudinal edges of the plate 1 and these fingers are adapted to exert an inward tension sufficient to bind the same upon either of the members 8 or 9 and to hold the bracket

in a properly adjusted position with relation to the guide brace members.

From the above description, taken in connection with the accompanying drawing, 5 the simplicity of the device, as well as the advantages thereof will, it is thought, be perfectly apparent to those skilled in the art to which such invention appertains without detailed description.

10 Having thus described the invention, what I claim is:

1. In a device for the purpose set forth, a hanger formed from a flat plate having an angular end provided with a downturned lip, its opposite end provided with outwardly disposed angular spring fingers arranged in spaced pairs, a guide brace comprising two telescopic members each having their longitudinal edges formed with inwardly flanged 15 spring members, the flanges of one of the members adapted to be received by the flanges of the other member, said members being arranged to be contacted by the fingers of the bracket member, a locking element 20 between the members, each of the said members having its outer edge formed with a

right angular extension, and the said extension being provided with inturned teeth.

2. In a device for the purpose set forth, 30 a hanger including a member having an angular end provided with a downturned lip and its opposite end formed with outwardly disposed angular spring fingers arranged in spaced pairs, a guide brace comprising two telescopic members each having their 35 ends flanged and said flanges formed with inturned teeth, the inner member having its longitudinal edges flanged and the said flanges being engaged by the referred to spring fingers of the hanger member, and an 40 adjustable locking element upon the outer telescopic member adapted to contact with the inner member to force the edges of the said outer member into contacting engagement with the flanges of the inner member. 45

In testimony whereof I affix my signature in presence of two witnesses.

JOHN F. DE HAVEN.
